CLAMPING FIXTURE FOR THE APPLICATION
OF WEBBING TO FURNITURE AND THE
LIKE

Clay C. Moore, Jr., Corpus Christi, Tex.

Application February 19, 1951, Serial No. 211,668

5 Claims. (Cl. 144—297)

1

The present invention relates to improvements in clamping apparatus and more particularly to an apparatus which is adapted to be employed in combination with a clamp such as a C-clamp or a pipe clamp and a band or webbing such as canvas belting or upholsterer's webbing whereby reconditioning of furniture can be accomplished in an effective manner.

An object of the present invention is to provide a clamping apparatus that is particularly adapted for holding the several elements in assembled relation while the glue joining the several elements is drying.

Another object of the present invention is to provide an improved clamping apparatus which can be employed in combination with a C-type clamp whereby a strip of upholsterer's webbing can be disposed about the seat portion of an article of furniture to retain the springs in position for tying and like operations.

A further object of the present invention resides in the durable construction of the clamping apparatus and the cooperation between the blocks which comprise the main elements of the apparatus.

A still further object of the present invention resides in the provision of means for retaining the upholsterer's webbing in clamped relation with respect to preselected of the blocks of the clamping apparatus whereby as the C-clamp is tightened on the plurality of blocks, the upholsterer's webbing disposed over the seat portion of the article of furniture will become tensioned.

Another object of the present invention is to provide novel means for clampingly securing the upholsterer's webbing to the preselected of the blocks.

Another object of the present invention is to provide a plurality of blocks which are slidably supported on a pair of slide rods in parallel relation to each other whereby the upholsterer's webbing can be disposed over the blocks and around the end blocks, thereby to frictionally maintain the webbing from sliding with respect to the surfaces of the blocks during clamping together of the several blocks.

Various other objects and advantages will become apparent from the detailed description to follow.

The best forms in which I have contemplated applying my invention are illustrated in the accompanying drawings, wherein:

Figure 1 is a detailed perspective view showing the clamp apparatus of the present invention in combination with upholsterer's webbing and a C-

2

clamp with the various elements in clamping relation;

Figure 2 is a vertical longitudinal sectional view through the clamping apparatus and showing the C-clamp in phantom lines;

Figure 3 is a detailed perspective view of the clamping apparatus showing the several blocks disposed in spaced relation on the slide rods;

Figure 4 is a longitudinal vertical sectional view taken substantially along the plane of line 4—4 of Figure 5;

Figure 5 is a vertical transverse sectional view taken substantially along the plane of line 5—5 of Figure 4;

Figure 6 is a vertical transverse sectional view taken substantially along the plane of line 6—6 of Figure 4;

Figure 7 is a detail perspective view of a modified form of means for clamping the upholsterer's webbing to preselected of the blocks; and

Figure 8 is a vertical sectional view through the clamping means of Figure 7.

Referring more particularly to the drawings, wherein like numerals designate like parts throughout, the numeral 10 designates generally the clamping apparatus which is to be employed in combination with the upholsterer's webbing 12 and a conventional C-clamp 14.

The device of the present invention is particularly adapted for use in the repairing or reconditioning of furniture, such as antiques. The means of the present invention is adapted to be employed when positioning the upholsterer's webbing over the seat portion or like portions of an article of furniture whereby the springs within the article of furniture are retained in compressed relation for tying or like operations.

The structure of the present invention is provided for tensioning the upholsterer's webbing whereby the springs will be held in compressed relation in a manner more effective than has been heretofore possible.

The webbing 12 is of conventional form, as is the C-clamp 14 which includes the body portion 16 and the clamp screw 18.

The clamping apparatus 10 is comprised of a pair of primary blocks 18 and 20 and a pair of secondary blocks 22 and 24. Each of the blocks 18 through 24 is provided with a pair of openings therethrough for receiving the slide rods 26 and 28. Thus, the plurality of blocks 18 through 24 are slidably received on the slide rods 26 and 28 and retained thereon by the enlarged head 30 and nut 32 on each of the rods.

As seen best in Figure 1, the clamping ap-

paratus of the present invention is adapted to receive the upholsterer's webbing 12 between the opposed inner faces 34 of the primary blocks 18 and 20 with the portion 36 of the upholsterer's webbing adapted to be disposed about an article of furniture to retain the springs of that article in compressed condition. Of course, the portion 36 is merely disposed about the springs and no great attempt is made to compress the springs by manual tensioning of the upholsterer's webbing. Rather, the upholsterer's webbing is disposed over the upper faces 38 of the primary blocks 18 and 20 with any one of the clamping means 40, 42 and 44 being employed for frictionally retaining the upholsterer's webbing 12 engaged on the upper surface of the primary blocks 18 and 20. The webbing is then extended over the outer faces 46 of the primary blocks 18 and 20 and over the bottom and outer faces 48 and 50 of the secondary blocks 22 and 24. The clamp end 52 is adapted to abut the upholsterer's webbing at 54 while the enlarged head 56 of the clamp screw is adapted to abut the upholsterer's webbing at 58 whereby the entire assembly can be urged into compressed relation.

The means 40, 42 and 44 can each be employed for frictionally retaining the upholsterer's webbing 12 on the upper surfaces 38 of the primary blocks 18 and 20, the means employed being that which is preferred.

The clamping means 40 is comprised of a flat elongated plate 60 having a pair of openings through its outer ends. A pair of standards 62 and 64 are secured to opposite faces of the primary blocks by means of the pins or screws 66 extending through the enlarged portion 68. The upper ends of the standards 62 and 64 are threaded for receiving the wing nuts 70 and 72 whereby the elongated plate 60 can be clamped against the upholsterer's webbing 12. Wing nuts 70 which are adapted to clampingly urge the elongated plate 60 against the upholsterer's webbing 12 on the upper faces of the primary blocks.

The clamping or retaining means 42 is comprised of an elongated elastic band 76 which is stretched over the upper surface of the primary blocks and secured to the end faces of the primary blocks by means of pins 78. Thus, the elastic band 76 can be stretched while the upholsterer's webbing is inserted thereunder. Upon release of the elastic band 76, the webbing will be frictionally retained against the primary block.

The form shown in Figures 7 and 8 and designated by the numeral 44 is comprised of a pair of standards 80 having enlarged portions 82 adapted to be secured to the end faces of the primary blocks by means of the pins or screws 84. A transversely extending cam rod 86 has end eyelets 88 formed integrally therewith for receiving the upper ends of the standards 80. Internally threaded wing nuts 90 are engaged on the threaded ends of the standards for retaining the transverse rod 86 in predetermined parallel relation to the upper surface of the primary block about which it is disposed. A cam lever 92, having a cam surface 94, is rotatably received on the rod 86 by means of the bushing 96. When the cam lever 92 is in the position shown in Figure 8, the upholsterer's webbing 12 can be inserted through the space below the cam surface 94 and above the upper surface of the primary block. The cam lever 92 may then be rotated to the position shown in dotted lines 92' whereby the cam surface 94 is rotated

for frictional engagement with the webbing to retain the webbing from movement relative to the primary block against which it is clamped. If desired, a plate such as plate 60 can be employed for use in combination with the cam lever. The plate 60 would be disposed beneath the cam lever and on the standards.

In view of the foregoing, it will be seen that the webbing can be disposed over a preselected portion of the article of furniture to be repaired or around the several elements of an article of furniture to be glued together. The webbing is then inserted through the clamping apparatus in the manner shown in Figure 1 with the clamping means adapted to frictionally retain the webbing against the upper surfaces of the primary blocks. The C-clamp 14 is then engaged over the several blocks and against the portions of the webbing overlying the end faces of the secondary blocks. By screwing the clamp screw 18 toward the enlarged head 52 of the C-clamp, the several blocks will be urged together, thereby further tensioning the webbing 12 about the piece of furniture. In this manner, the springs disposed between the webbing can be compressed for tying operations or the like of the several elements of the article will be maintained in assembled relation. Of course, the disposition of the primary and secondary blocks before the clamping of the C-clamp of effected is as shown in Figure 3 whereby tensioning of the webbing can be effectively obtained as a result of the movement of the blocks into close relation.

Having described my invention, what I claim as new is:

35. 1. A clamp apparatus comprising a plurality of rectangular shape blocks, means for slidably supporting said blocks whereby said blocks can be slid toward and away from each other, and adjustable means on preselected of said blocks for frictionally retaining upholsterer's webbing in preselected relation to said blocks, said blocks including primary and secondary blocks, said primary blocks being engageable with each other and adapted to receive the upholsterer's webbing between their inner and over their upper faces, and means urging said blocks toward one another, said adjustable means extending over the upper face of each primary block.
40. 2. A clamp apparatus comprising a plurality of blocks, means for slidably supporting said blocks whereby said blocks can be slid toward and away from each other, and means on preselected of said blocks for frictionally retaining upholsterer's webbing in preselected relation to said blocks, said primary blocks being engageable with each other and adapted to receive the upholsterer's webbing between their inner and over their upper faces, and means urging said blocks toward one another.
45. 3. A clamp apparatus comprising a plurality of blocks, means for slidably supporting said blocks whereby said blocks can be slid toward and away from each other, and adjustable means on preselected of said blocks for frictionally retaining upholsterer's webbing in preselected relation to said blocks, said primary blocks being engageable with each other and adapted to receive the upholsterer's webbing between their inner and over their upper faces, and means urging said blocks toward one another.
50. 4. A clamp apparatus comprising a plurality of blocks, means for slidably supporting said blocks whereby said blocks can be slid toward and away from each other, and adjustable means on preselected of said blocks for frictionally retaining upholsterer's webbing in preselected relation to said blocks, said primary blocks being engageable with each other and adapted to receive the upholsterer's webbing between their inner and over their upper faces, and means urging said blocks toward one another.
55. 5. A clamp apparatus comprising a plurality of blocks, means for slidably supporting said blocks whereby said blocks can be slid toward and away from each other, and adjustable means on preselected of said blocks for frictionally retaining upholsterer's webbing in preselected relation to said blocks, said primary blocks being engageable with each other and adapted to receive the upholsterer's webbing between their inner and over their upper faces, and means urging said blocks toward one another.
60. 6. A clamp apparatus comprising a plurality of blocks, means for slidably supporting said blocks whereby said blocks can be slid toward and away from each other, and adjustable means on preselected of said blocks for frictionally retaining upholsterer's webbing in preselected relation to said blocks, said primary blocks being engageable with each other and adapted to receive the upholsterer's webbing between their inner and over their upper faces, and means urging said blocks toward one another.
65. 7. A clamp apparatus comprising a plurality of blocks, means for slidably supporting said blocks whereby said blocks can be slid toward and away from each other, and adjustable means on preselected of said blocks for frictionally retaining upholsterer's webbing in preselected relation to said blocks, said primary blocks being engageable with each other and adapted to receive the upholsterer's webbing between their inner and over their upper faces, and means including a member extending over the upper face of each primary block, and a C-clamp engageable with the outer faces of the outermost blocks for urging the blocks into en-

gagement with each other for tensioning the upholsterer's webbing over an article of furniture.

4. A clamp apparatus comprising a plurality of spaced, rectangular-shaped blocks having side, end, top and bottom walls, the side walls of said blocks being disposed in parallel relation to one another, each block having a pair of bores extending therethrough adjacent the side wall edges, said blocks being disposed with the bores in axial alignment, rods slidably extending through said aligned bores and connecting said spaced blocks to one another, adjustable means extending over the top wall of at least one of said blocks and being connected to the end walls of said block to frictionally retain a flexible member between the top wall of said block and said adjustable means, and means urging said blocks towards one another whereby the flexible member may be clamped between opposing side walls of said blocks, said adjustable means comprising a pair of standards, each standard having one end secured to an end wall of said block and having a free threaded end extending above said block, a clamping plate extending over the top wall of said block and being slidably journaled at its ends on said standard and means on said standards to press said plate into engagement with said top wall.

5. A clamp apparatus comprising a plurality of spaced, rectangular-shaped blocks having side, end, top and bottom walls, the side walls of said blocks being disposed in parallel relation to one another, each block having a pair of bores ex-

tending therethrough adjacent the side wall edges, said blocks being disposed with the bores in axial alignment, rods slidably extending through said aligned bores and connecting said spaced blocks to one another, adjustable means extending over the top wall of at least one of said blocks and being connected to the end walls of said block to frictionally retain a flexible member between the top wall of said block and said adjustable means, and means urging said blocks towards one another whereby the flexible member may be clamped between opposing side walls of said blocks, said adjustable means comprising a pair of standards each standard having one end secured to an end wall of said block and having a free threaded end extending above said block, a rod extending over the top wall of said block and being adjustably secured at its ends to said standards, a camming member secured on said rod intermediate its ends.
